S. ZETLIN

REINFORCED DETACHABLE POCKET

Filed Sept. 2, 1924

Fig. 1.

Fig. 2.

Inventor:

Samuel Zetlin.

Attorney-

Sterling P. Buck.

UNITED STATES PATENT OFFICE.

SAMUEL ZETLIN, OF BALTIMORE, MARYLAND.

REINFORCED DETACHABLE POCKET.

Application filed September 2, 1924. Serial No. 735,452.

To all whom it may concern:

Be it known that I, SAMUEL ZETLIN, a citizen of the United States, residing at Baltimore city, in the State of Maryland, have invented certain new and useful Improvements in Reenforced Detachable Pockets, of which the following is a specification.

This invention relates to garment-pockets, especially to an improved reenforced detachable pocket, and more specifically to an improved self-secur ing feature of such detachable pocket.

The main object of the present invention is to provide an exceedingly simple and thoroughly effective reenforced removable pocket that is especially useful for railway conductors and others who collect fares and other moneys, which is devoid of metal parts that rust or corrode, and which includes, as an inherent element, an efficient means to prevent the removable pocket from becoming accidentally detached or raised out of the permanent pocket or slit in which it is contained when being used.

Another object is to provide a pocket of excessive strength and stability consistent with the important features of flexibility and ease of access to its interior, at the same time providing comparatively smooth rounded margins of the pocket's mouth, to facilitate quick and comfortable entrance and exit of the hand of the user.

Other objects and important features will be pointed out or implied in the following details of description, in connection with the accompanying drawings, in which,—

Fig. 1 is an elevation or face view, and Fig. 2 a vertical sectional view, the sectional plane being along the line 2—2 of Fig. 1.

Referring to these drawings in detail, in which similar reference numerals correspond to similar parts throughout the several views:—

The pocketing or bag 1 may be of any preferred material and of any appropriate shape, but is preferably of the shape shown, including downwardly diverging sides, being considerably broader at the bottom than at the central and upper part, and having shoulders 2 at the upper ends of the diverging sides, the mouth or opening 3 of the pocketing or bag being considerably narrower or shorter than the width of the main part of the pocketing or bag.

A reenforcing and attaching sheet or plate 4 preferably includes a sheet 4^a of leather or

the like and a sheet 4^b of cloth, which latter may be of any appropriate and preferred kind and color, and the cloth sheet is larger than the leather sheet and has its edges extending beyond all edges of the leather sheet and thus provides a very convenient and effective stitch-receiving border or margin 5 through which the protecting plate may be sewed to the coat or other garment having a permanent pocket in which this removable or detachable pocket may be placed, or to such coat or garment that has a horizontal slit into which the pocketing or bag of this pocket may be placed in lieu of a stationary pocket. It should be understood that this device is most effective, useful and economical when the coats or other garments are made with such horizontal slits, eliminating the permanent pockets, in which case, the manufacturing cost is greatly reduced, and the ends of the pocket-slits positively lock over the shoulders 2 and effectively prevent displacement of the detachable pocket even if the user of the garment neglects to securely stitch or pin the edges 5 of the cloth plate to the garment. Moreover, the general enlargement of the pocketing or bag, beyond the extent of the slit which fits around the part above the shoulders 2, makes it difficult to accidentally remove the pocket, especially when its bottom is filled with coins which press laterally against the ends and sides of the pocketing or bag and causes it to bind in the permanent pocket when used in such permanent pocket.

The leather sheet 4^a is substantially plane throughout its extent and has a slit 3^a through its central part, and solid or inherently united parts of this sheet separate the ends of this slit from the marginal edges of the leather sheet. The shape of the cloth sheet is substantially the same as that of the leather sheet, and its central slit is in registration with that of the leather slit, the ends of its slit being separated from its marginal edges by inherently united or solid parts. These solid ends of the registering slits combine to offer excessive resistance to any tendency of the slits to become extended by tearing or ripping as where such slits are not terminated in such solid parts. Marginal seams 5^a secure the margin of the leather sheet 4^a to the cloth sheet 4^b. A leather binding and protecting strip 6 embraces the lower or front edge of the bag's mouth and the contiguous edges of the cen-

tral slits of the plates or sheets 4^a and 4^b, and a row of stitching 6^a secures these contiguous edges to one another in such relation that the strip 6 is curved over the contiguous edges and forms a comparatively smooth and pliable piping which facilitates the ease and comfort with which the hand of the user can enter the pocket.

From the foregoing, it may be seen that the 10 plates or sheets 4^a and 4^b combine, not only to form the substantial piping at 6, but also exert their combined strength in supporting the bag 1 when heavily loaded with coin or the like, in addition to providing the securing edge or margin 5 in which a long marginal seam may be made to unite it with the coat or other garment from which it may be detached by merely ripping this latter seam.

I do not intend to limit my patent-protection to the exact construction and arrangement here shown, but claim all equivalent constructions within the scope of the invention, as implied and claimed herein.

What I claim is:

25 As an article of separate manufacture adapted to be attached to and detached from a garment having a slit therein, a pocket

comprising a bag adapted to be extended through said slit, a substantially plane leather sheet having a slit through its central part, a substantially plane cloth sheet having a slit through its central part in registration with said slit of the leather sheet, the ends of these registering slits being separated from the margins of said sheets by means of solid parts of both plates, a leather binding and protecting strip extending through the registering slits and embracing these sheets and an edge of the bag's opening, stitching securing said binding and protecting strip to said sheets and bag in the relation for forming a substantial piping at the bag's opening, and a marginal row of stitching securing the margin of said leather sheet to said cloth sheet, the margin of said cloth sheet extending freely beyond all outer edge portions of said leather sheet and thus providing a convenient and durable means for attaching and detaching and re-attaching the pocket to a garment or garments by 45 pins or stitching.

In testimony whereof I affix my signature.

SAMUEL ZETLIN.
